Application October 15, 1929. Serial No. 399,845

39 Claims. (Cl. 74—7)

This invention relates to starters for internal combustion engines and more particularly to the type in which a starter pinion is moved manually into meshing engagement with an engine gear 5 and is automatically demeshed when the engine is started.

Heretofore in starters of this type the starter pinion has been moved axially and then if necessary, moved rotarily in one direction to mesh the 10 pinion with the engine gear. Should the teeth of the pinion meet corner to corner with those of the gear, or be otherwise obstructed to prevent the turning of the pinion, a jam will result which might require several operations of the starter 15 mechanism to effect the meshing of the pinion.

The object of this invention is to provide a starter which will overcome the above mentioned objectionable jamming feature, and which will prevent the pinion from bouncing back into contact with the gear after it has been de-meshed therefrom. Other objects we have in mind will hereinafter appear.

We attain our objects by means of the constructions briefly described as follows. A slide- 25 able and rotatable member sleeve disposed on the armature shaft of the starter motor has a disengageable driving connection with a starter pinion which is threaded on the shaft. A manually operable member has a pin and a spring finger for frictional engagement with an inclined lug on the slideable and rotatable member or sleeve whereby the latter will be actuated to move the pinion axially and, if necessary, rotarily to mesh it with the engine gear. If the pinion fails to mesh during 35 this rotary movement, the manually operable member will continue its movement to engage the pin with other provisions for turning the sleeve in a direction of rotation opposite to the first mentioned rotary movement thereof so that the pinion 40 may be turned first in one direction of rotation and then in the opposite direction. This second rotary movement of the pinion is especially adapted to release a corner jam between the pinion and the gear teeth which might occur during 45 the first movement of the pinion. When the pinion is meshed with the gear the starter motor is energized to drive the engine and to cause the sleeve to turn to engage a cam face thereon with the pin. This engagement causes the sleeve to be threaded back to its initial position. The sleeve 50 is provided with an opening to receive the pin if the engine gear be moving in a backward direction when the pinion is moved into contact therewith.

55 During the return movement of the sleeve an

anti-bounce device movable therewith is moved relative thereto towards the pinion to absorb its momentum when it is de-meshed from the gear.

The constructions are hereinafter more fully described and are illustrated in the accompanying drawings in which

Fig. 1 is a side elevation of our starter showing the parts thereof in their normal or inoperative positions;

Fig. 2 a development of part of the surface of 65 the outer member of the starter, showing particularly the cam faces for engagement by a manually operable member;

Fig. 3 a longitudinal section of the parts dis- 70 posed on the shaft in Fig. 1;

Fig. 4 a cross section, showing the pin and 75 spring finger on the manually operable member in engagement with the lug on the outer sleeve, and also showing the drag connection between the anti-bounce device and the shaft;

Fig. 5 a longitudinal section, partly in elevation, showing the pinion clutched to the outer 80 sleeve and in contact with the gear teeth, and also the manually operable pin and finger in frictional engagement with the lug on the outer sleeve;

Fig. 6 a view similar to Fig. 5, showing the pinion still in contact with the gear teeth and the manually operable pin in engagement with the cam face for reversing the rotary movement 85 of the outer sleeve;

Fig. 7 a view similar to Fig. 6, showing the pinion slightly in mesh with the gear and the manually operable member still clear of the 90 motor switch;

Fig. 8 a view similar to Fig. 7 showing the rotatable member returned to its normal position and the anti-bounce device positioned for engagement by the pinion when it is de-meshed;

Fig. 9 a view showing the positions of the parts 95 should the pinion be presented to the gear while the latter is moving;

Fig. 10 a view similar to Fig. 6 showing the positions of the parts if the starter fails to mesh 100 the pinion;

Fig. 11 a detail showing the outer sleeve being turned by the shaft to prevent the engagement of the pin and finger with the lug when the shaft is rotating;

Fig. 12 a side elevation partly in section of a modified form of our starter;

Fig. 13 a development of part of the surface of 110 the outer and intermediate sleeves shown in Fig. 12.

Fig. 14 a side elevation of a further modified form of starter;

Fig. 15 a development of the outer sleeve shown in Fig. 14;

5 Fig. 16 a longitudinal section of another modification; and

Fig. 17 a development of the intermediate and outer sleeves shown in Fig. 16.

Referring to Figs. 1 to 11, 1 is a motor provided with an armature shaft 2 on which is mounted a sleeve 3. A C-shaped spring 4 encircling slightly more than half of the sleeve is provided with a pin 5 which passes through a hole in the sleeve to contact with the shaft so that the latter, 10 when rotating, will tend to rotate the sleeve for purposes which will hereinafter appear.

On the sleeve is disposed a clutch member 6 which is provided with clutch teeth 7 adapted to form a disengageable drive connection with 20 similarly shaped teeth 8 formed on the ends of the teeth of a pinion 9. To increase the length of the teeth 7 and to facilitate the stamping of the clutch member, the teeth are inclined to the axis of the member. The clutch teeth 8 on 25 the pinion are similarly inclined. The clutch member is provided with a plurality of projections 10 which are received in slots 11 formed in a rotatable outer member or sleeve 12 so that these clutch and sleeve members 6 and 12 30 have a limited axial movement relative to one another to permit the overrunning of the clutch teeth. The outer sleeve 12 is provided with a collar 13 having a pin and inclined slot connection 14 with the inner sleeve 3. A spring 15 35 engaging the collar 13 and the clutch member 6 tends to maintain the latter in an extended position relative to the outer sleeve 12 and is of such strength and the teeth 7, 8 are so shaped that the clutch member 6 is capable of turning 40 the pinion 9 and the armature shaft 2 under normal conditions that is when the turning movement of the pinion is normally resisted.

The outer sleeve 2 is moved axially and 45 rotationally to mesh the pinion by means of a lever 16 which is manually operable by a foot pedal or hand pull-out device 17. The lever is provided with a pin 18 adapted to engage a cam face 19 preferably formed by a slot in the outer sleeve 12. The latter is provided with a lug 19^a having one 50 side flush with the cam face 19. A spring finger 20 carried by the lever 16 and normally positioned out of engagement with the lug is adapted to engage one side thereof while the pin is in engagement with the other side of the lug, whereby 55 the latter will be frictionally gripped between the pin and finger to tend to move the outer sleeve 12 along with the pin and finger, see Fig. 5. This axial movement of the outer sleeve 12 will cause the clutch member 6 to be moved to engage its teeth 7 with the clutch teeth 8 on the pinion so that the latter will be presented to the gear 21 of an engine to be started. The inner sleeve 3 is provided with a flange 3^a which is engageable by the clutch member 6 for moving the inner sleeve along 60 with the outer sleeve 12.

If the pinion teeth are in alignment with the spaces between the gear teeth when the pinion reaches the gear the continued axial movement 70 of the outer sleeve 12 will move the pinion into engagement with an abutment 22. Under normal conditions with the gear 21 at rest, the end 16^a of the lever 16 is adapted to actuate a switch 23 to energize the motor 1 only when the pinion is in mesh with the gear. When the pinion is meshed

without any rotary movement it will engage the abutment 22 before the lever end 16^a reaches the switch 23 whereby the further movement of the lever to close the switch causes the pin 18 and finger 20 to move out of engagement with the lug 19^a before the motor is energized. This movement of the pin and finger relative to the lug causes the member 12 to be turned relative to the pinion which relative movement is permitted by the clutch which is adapted to slip when rotation of the pinion is abnormally resisted. Immediately the shaft 2 is rotated by the motor to drive the pinion, the outer sleeve 12 is also rotated, by means of the drag connection 5, inner sleeve 3, and the pin and inclined slot connection 14, 80 whereby the pin 18 will be engaged by a cam face 24 on the member 12 to return the latter to its initial position against a brake washer 25.

During the return movement of the outer sleeve 12, the inner sleeve 3 is axially moved relative thereto to position one end of it behind the adjacent end of the outer sleeve so that the inner sleeve will be engaged by the pinion when the latter is de-meshed by the gear, see Fig. 8. This relative axial movement of the inner and outer sleeves 3 and 12 is effected by the pin and inclined slot connection 14, the slot of which is formed in the sleeve 3. The pin of this connection is formed as a key stamped out of the collar 13 which is secured to the outer sleeve 12, 95 see Fig. 3. The slot thus drives the pinion or key of the connection 14 to rotate the outer sleeve 12 to enable it to be returned as hereinbefore described and during this rotary and axial movement of the outer sleeve the inner sleeve 3 is left 100 behind. In other words, the outer sleeve is threaded, by the pin 18 and cam face 24, away from the pinion and the pin and inclined slot connection 14 between the outer and inner sleeves permits movement of the outer sleeve relative to 105 the inner sleeve. The relative axial movement of these sleeve parts is terminated by the engagement of the C-spring 4 and pin 5 on the inner sleeve with the collar 13 on the outer sleeve and the inner sleeve is then moved with the outer 110 sleeve to provide clearance for the pinion so that it will be free of the gear before it engages the inner sleeve, as indicated in dotted lines in Fig. 3.

When the engine starts the pinion will be automatically de-meshed by its inclined spline connection 2^a with the shaft 2 and the momentum of the pinion will be absorbed by the inner sleeve 3 while the pinion is shifting it to its initial position, which is also determined by the brake washer 25, see Fig. 3. If the de-meshed pinion engaged a rigid stop the pinion might bounce back into contact with the gear with resultant bad effects and the inner sleeve 3 serves as an anti-bounce device to overcome this objectionable feature. Normally the flange 3^a on the inner sleeve or anti-bounce member 3 positions the pinion to prevent its clutch teeth 8 from engaging the clutch teeth 7 on the clutch member 6 so that the shaft and pinion are free to rotate relative to the clutch member until the operator removes his foot from the starter button 17.

If the pinion teeth should collide with the gear teeth, the axial movement of the clutch member 6 will be stopped, see Figs. 5 and 6. Therefore the continued movement of the manually operable 145 lever 16 will cause the pin and finger to travel along the lug 19^a to rotate the outer sleeve 12 and thus the pinion 9. It is obvious that the engagement of the pin 18 and spring finger 20 with the lug will ensure contact between the pinion teeth 150

and the gear teeth while the pinion is being turned and will also ensure the axial movement of the pinion into mesh with the gear immediately the pinion teeth clear the gear teeth. If the pinion is partly meshed with the gear but is not in engagement with the abutment 22 before the lever end 16^a closes the switch 23, the threads 2^a on the shaft, when the latter is driven by the motor 1, will feed the pinion axially thereof into engagement with the abutment.

Should the above mentioned rotary movement of the pinion fail to clear its teeth from those of the gear or should a corner jam occur between the pinion teeth and the gear teeth, provisions are provided for engagement by the pin 18 to turn the pinion in a direction of rotation opposite to that imparted thereto by the engagement of the pin with the cam face 19. This reverse turning of the pinion is caused by the engagement of the pin 18 with a cam face 28 which may be formed by a slot in the outer sleeve 12 and which is inclined to the axis thereof in a direction opposite that of the cam face 19, see Fig. 6. The cam face 28 is spaced from the cam face 19 but lies in the path of the pin 18 and has a steep angle of inclination to the axis of the member whereby the force tending to move the latter longitudinally is greater than the force tending to move it rotarily. If the pin 18 is in engagement with the cam face 19 when the first mentioned rotary movement of the pinion is stopped by abnormal resistance to its further turning in the direction of rotation produced by the engagement of the pin 18 and cam face 19, the continued movement of the pin 18 along the cam face 19 rotates the outer sleeve 12 relative to the pinion because the clutch can slip. This slippage of the clutch is facilitated by the pin and inclined slot 14 which limits the axial movement of the outer sleeve 12 relative to the inner sleeve 3 and thus to the pinion 9, so that the projections 10 on the clutch member 6 are normally spaced from the rear edges of the slots 11 in the outer sleeve 12 and are thus free to move in the said slots 11 to provide clearance for the clutch teeth 7 when they overrun the clutch teeth 8 on the pinion. A continued movement of the pin 18 after it engages the cam face 28 will result in the outer sleeve 12 and thus the pinion 9 being turned in a reverse direction. It is obvious that this reverse movement of the pinion will relieve the teeth thereof from the teeth of the gear should a corner jam occur during the turning of the pinion by the engagement of the pin 18 and cam face 19. Immediately the pinion teeth clear the gear teeth, the pinion will thus be moved, by the pressure exerted by the pin 18 against the cam face 28, into mesh with the gear, see Fig. 7. When the pinion is meshed, the end 16^a of the lever 16 will close the switch 23 to energize the motor 1 as hereinbefore described.

Should the hereinbefore described axial and double rotary movements in opposite directions of the pinion 9 fail to mesh it with the gear 21, we provide means for limiting the movement of the lever 16 to prevent it from closing the switch 23. The cam face 28 may terminate in a shoulder 30 adapted to limit the movement of the pin 18 relative to the outer sleeve 12 in case the pinion is not meshed with the gear. This axial movement of the sleeve 12 relative to the pinion is limited by the pin and slot connection 14 so that if the spring 15 be compressed by the pressure of the pin 18 against either the cam face 28 or shoulder 30 the said connection 14 will limit the movement of the lever 16 to prevent the motor 1

from being energized. In other words, the pin and slot connection 14 limits the axial movement of the outer sleeve 12 relative to the inner sleeve 3 so that the pin 18 cannot be moved a sufficient distance to enable the lever 16 to close the switch when the axial movement of the pinion, and thus the inner sleeve, is prevented by the gear.

If the pinion should be presented to the gear while the latter is rotating in its normal direction of rotation, the pinion 9 and thus the shaft 2 and outer sleeve 12 will tend to be turned by the gear 21 in their normal direction of rotation and the pin 18 will be received in the slot forming the cam face 24.

To prevent the parts from being damaged, if the pinion be presented to the gear while it is moving in a backward direction of rotation, we provide an opening 29 which provides clearance for the pin 18. The contact between the gear and pinion teeth causes the pinion and thus the outer sleeve 12 to vibrate so that the pin 18 slides along the cam faces 19 and 28. It will be noted that the switch protection shoulder 30 is steeply inclined to the axis of the outer sleeve, the inclination being such that the above mentioned vibration of the outer sleeve will permit the shoulder to clear the pin 18 and thus relieve further pressure tending to force the pinion against the gear, see Fig. 9. One face 29^a of the opening is inclined to the axis of the outer sleeve in a direction opposite that of the cam face 24 whereby the engagement of the cam face 29^a with the pin 18 will tend to return the outer sleeve 12 to its initial position. Should the operator continue the movement of the lever 16 until it closes the switch 23, the shaft 2 and outer sleeve 12 will be turned in their normal direction of rotation whereby the face 29^b of the opening 29 will engage the pin 18 to return the outer sleeve to its initial position. The cam faces 29^a and 29^b, formed by the walls of the slot or opening 29, are inclined in opposite directions, the face 29^b being substantially parallel to the cam face 24 so that the engagement of either of these faces with the pin 18 will return the outer sleeve 12 when it is rotated in its normal direction of rotation.

The mode of operation is as follows. Assuming the shaft 2 and engine gear 21 are at rest when the operator actuates the lever 16, the pin 18 and spring finger 20 will be moved to embrace the lug 19^a whereby the outer sleeve 12 will be moved axially to engage the clutch teeth 7 and 8 and present the pinion 9 to the gear. If the teeth of the pinion do not collide with the teeth of the gear the axial movement of the pinion is continued until it engages the abutment 22. The movement of the lever 16 is continued until it closes the switch 23 to energize the motor 1, in which case the finger 20 and pin 18 will be clear of the lug 19^a. If the teeth of the pinion collide with the gear teeth, the axial movement of the pinion and clutch member 6 is stopped and the pin 18 slides along the cam face 19 to turn the outer sleeve 12 and thus the pinion while its teeth are in contact with the gear teeth. If the pinion meshes with the gear while the lug 19^a is engaged by the pin 18 and finger 20, the frictional engagement of these parts will cause the pinion to be moved fully into mesh with the gear. If meshing occurs as finger 20 moves out of engagement with lug 19^a, the pin 18 will engage the cam face 28 to fully mesh the pinion. If the turning of the pinion is abnormally resisted, as in a corner jam, the clutch teeth 7 and 8 will permit the outer sleeve 12 to turn

150

sufficiently to allow pin 18 to move off cam face 19 and engage cam face 28. The spring 15 may be compressed during the movement of the pin 18 along the cam face 19 so that the cam face 28 will be forced against the pin when the latter disengages the face 19. This will tend to loosen the pinion teeth from the gear teeth, and thus assist the meshing of the pinion. If the pinion teeth are still abutting the gear teeth or are locked in a corner jam therewith, the pin 18 will ride over the cam face 28 to reverse the direction of rotation of the pinion, and thus clear its teeth to permit the pin 18 to move the outer sleeve axially. As the spring 15 is compressed during this reverse movement of the pinion it tends to move the pinion into mesh with the gear immediately registration is effected. When the pinion is meshed and the motor 1 energized, the outer sleeve 12 is rotated, by means of the drag connection 5, inner sleeve 3 and pin and slot connection 14, to engage the cam face 24 with the pin 18 so that the outer sleeve 12 will be returned to its initial position with the inner sleeve 3 extending therefrom for engagement by the pinion when the engine is started. If pin 18 be engaged with cam face 28 when motor 1 is energized, the outer sleeve 12 will be turned, by the pinion 9 and the clutch teeth 7, 8, to move the face 28 out of engagement with the pin and to move the return cam face 24 into engagement therewith.

If the lever 16 be operated to mesh the pinion while the shaft 2 is spinning, the outer sleeve 12 will turn with the shaft to maintain the return cam face 24^a in engagement with the pin 18 whereby the finger 20 will be prevented from engaging the lug 19^a to move the sleeve 12 axially.

Any suitable device such as an arm 32 movable with the lever 16 may be employed to prevent the pinion 9 from contacting accidentally with the gear 21 while it is running.

In Figs. 12 and 13 we show a slightly modified outer member which is formed in two sleeve parts, 12^c and 33. The intermediate sleeve 33 is provided with projections 34 received in slots 35 in the outer sleeve 12^c. A clutch member 6^c disposed on the inner sleeve 3^c is provided with laterally directed clutch teeth 7^c for engagement with similarly shaped teeth 8^c formed on the ends of the teeth of a pinion 9^c. A spring 15^c engages a collar 13^c and the intermediate sleeve 33 to tend to maintain the latter and the clutch member 6^c in their extended positions relative to the outer sleeve 12^c. The slots 35 and 11^c are of sufficient length to facilitate overrunning of the clutch teeth 7^c, 8^c when the pin and inclined slot connection 14^c, between the inner sleeve 3^c and the outer sleeve 12^c, prevents the axial movement of the latter relative to the pinion as shown in Fig. 12. The action of this form of starter is exactly the same as that of the hereinbefore described starter, the only difference being that the intermediate sleeve 33 is provided to carry the reverse cam face 28^c. When the pin 18^c is moved out of engagement with the cam face 19^c it engages an inclined face 30^c on the outer sleeve 12^c which face normally covers the cam face 28^c.

If the pinion teeth be partly in mesh with the gear teeth or in alignment with the spaces between the latter, the pressure of the pin against the face 30^c will move the outer sleeve and thus the intermediate sleeve and the clutch member to mesh the pinion. Should the pinion teeth be

abutting the gear teeth when the pin 18^c engages the face 30^c the pin will move the outer sleeve relative to the intermediate sleeve 33 and clutch member 6^c to present the cam face 28^c to the pin whereupon the sleeves and clutch teeth 7^c, 8^c and thus the pinion will be turned in a direction of rotation opposite that imparted thereto by the engagement of the pin and cam face 19^c. If the pinion teeth are brought into meshing relationship with the gear teeth during this reverse turning movement thereof, the spring 15^c will move the intermediate sleeve and clutch member to their normal positions relative to the outer sleeve so that when the starting motor is energized the cam face 28^c is out of the path of the pin while the outer sleeve 12^c is being turned to engage its return cam face 24^c with the pin.

It will be noted that one end of the face 30^c projects beyond the end of the cam face 28^c for engagement by the pin 18^c if the pinion is not meshed when the pin moves past the end of the cam face 28^c. During these rotary movements the outer sleeve 12^c has been moved relative to the inner sleeve 3^c so that the pin or key of the pin and slot connection 14^c has reached the outer end of the slot whereby any further axial movement of the outer sleeve is prevented by the pinion and inner sleeve and thus the lever 16^c is prevented from closing the switch 23^c.

In Figs. 14 and 15 a further modified form of our starter is shown, in which the pin 18^f must engage a reverse cam face 28^f to reverse the direction of rotation of the outer sleeve 12^f before the pinion 9^f can be meshed with the gear. A converse arrangement of the pin 18, spring finger 20, cam face 19 and lug 19^a shown in Figs. 1 to 11 is shown in Figs. 14 and 15 in which the pin 18^f and finger 20^f are passed between the cam face 19^f and lug 19^a instead of being passed along the opposite sides of the latter. To ensure the pin 18^f being clear of the reverse cam face 28^f before the starter motor can be energized, we provide the outer sleeve 12^f with a lip 36 adapted to engage an abutment 37 which limits the axial movement of the outer sleeve. With this arrangement, if the pinion be meshed while the pin and finger are engaged with the cam face 19^f and lug 19^a, the pinion and the sleeve 12^f will be moved along the shaft until the lip engages the abutment 37. It will then be necessary to continue the movement of the lever 16^f relative to the sleeve to move the pin 18^f past the reverse cam face 28^f before the switch can be closed. During this operation the pin 18^f does not engage the switch protection shoulder 30^f so that member 12^f is free to be rotated by the hereinbefore described drag connection (not shown in Figs. 14 and 15) when the starter motor is energized.

Of course the engagement of the lip 36 with the abutment 37 limits the axial movement of the sleeve 12^f whether the pinion be meshed with its gear while the pin 18^f and finger 20^f be engaged with the cam face 19^f and lug 19^a as above described, or while the pin 18^f be engaged with the reverse cam face 28^f or whether the pinion is not meshed. In the last mentioned case the pin 18^f comes to rest against the switch protection shoulder 30^f and the lever 16^f is prevented from closing the switch 23^f.

Figs. 16 and 17 disclose a still further modification in which the pin 18^j is adapted to engage a lug 38 formed on an intermediate sleeve 39 which is slidably mounted on the inner sleeve 3^j. The outer sleeve 12^j is provided with cam faces 19^j and 24^j and opening 29^j and a shoulder 30^j. The lug

38 projects radially towards the outer member sleeve, is arranged at an angle to the axis thereof and is positioned, by means of a pin 40 and an inclined slot 41, for engagement by the pin 18^j as it moves along the cam face 19^j. The pin 40 is secured to the intermediate sleeve 39 and the inclined slot 41 is formed in the outer sleeve 12^j whereby a relative axial movement of the sleeves will position the lug 38 beyond the cam face 19^j so that they will serve to reverse the direction of rotation of the sleeve 12^j as shown in dotted lines in Fig. 17. A collar 13^j supports one end of the sleeve 12^j the other end of which is supported by the clutch member 6^j which is provided with a conical clutch surface 7^j adapted to frictionally engage a corresponding surface 8^j which may be formed on the teeth of the pinion 9^j. This conical type of clutch has an advantage over the hereinbefore described toothed clutches in that the conical clutch will set immediately its parts are engaged whereas there is a possibility of rotary movement being lost in the setting of the toothed clutches. The axial movement of the sleeve 12^j is limited by the engagement of a lip 36^j thereon and an abutment 37^j to ensure the pin 18^j being clear of the lug 38 when the starter motor is energized. A switch protection shoulder 30^j is adapted to engage the pin 18^j to prevent the manually operable lever from closing the switch should the double rotation of the pinion fail to mesh it with the gear. As in the modification shown in Figs. 14 and 15, the switch protection shoulder 30^j is not reached by the pin 18^j when the pinion is meshed with the gear and the lip 36^j is engaged with the abutment 37^j.

It is obvious that the pin 18^j (which corresponds to the pin 18 in Figs. 1 to 11, the pin 18^c in Figs. 12 and 13, the pin 18^f in Figs. 14 and 15) when moved to the left in Fig. 17 will engage the lug 38 and, if the teeth on the pinion are in proper meshing position relative to the teeth on the flywheel gear 21^j, the whole assembly by means of the intermediate sleeve 39 and spring 15^j is moved to the left until the pinion 9^j is properly meshed with the gear. If the pinion teeth abut those of the gear the motion of the pinion and the outer sleeve 12^j to the left is stopped and further movement of pin 18^j along the cam face 19^j will rotate the sleeve 12^j and thus the pinion 9^j in a downward direction of rotation in Fig. 17. The angle of the slot 41 is such that the lug 38 is maintained in engagement with 18^j as it travels along the cam face 19^j. This further movement of the pin 18^j moves the sleeve 39 axially relative to the sleeve 12^j against the compression of the spring 15^j so that the latter will cause the pinion to jump into engagement with the gear if the pinion teeth clear the gear teeth during the said rotary movement of the pinion.

If the rotation of the pinion in the direction of rotation above referred to is prevented by a corner jam of the pinion and gear teeth, the continued movement of the pin 18^j along the cam face 19^j will rotate the sleeve 12^j without turning the pinion, the clutch faces 7^j and 8^j being adapted to slip to permit such rotation of the said sleeve relative to the pinion, and will move the lug 38 beyond the cam face 19^j as indicated in dotted lines in Fig. 17. In this position the lug 38 has been moved to permit the pin 18^j to move between the lug and the adjacent end of the cam face 19^j and this position of the lug 38 is determined by the engagement of the end of the intermediate sleeve 39 with the clutch member 6^j. As any further axial movement of the lug 38 is thus pre-

vented and as the direction of inclination of the face of the lug engaged by the pin is opposite that of the cam face 19^j, a further movement of the pin will cause it to slide along the inclined face of the lug and turn the intermediate sleeve 39 and thus the outer sleeve 12^j and the pinion 9^j in an upward direction of rotation in Fig. 17 to bring the pinion to proper meshing position and the spring will cause its engagement with the gear as above set forth. The pin 18^j is carried by a lever (not shown) which is adapted to close the motor switch to effect rotation of the pinion and gear. In every case the axial movement of the sleeve 12^j is limited by the abutment 37^j so that continued movement of the pin 18^j will cause it to move past the lug 38 before the said lever can reach the motor switch. If the double turning of the sleeve 12^j has failed to mesh the pinion the switch protection shoulder 30^j will engage the pin 18^j to prevent the switch from being closed by further movement of the lever (corresponding to the lever 16 in Figs. 1 to 11; 16^c in Figs. 12, 13; and 16^f in Figs. 14, 15).

Assuming the pinion and gear have been meshed and the pin 18^j has been moved past the lug 38, the spring 15^j is then free to expand the sleeves 12^j and 39 which relieves the spring pressure on the clutch and the lever carrying the said pin is free to close the motor switch. Immediately the armature shaft 2 is driven, the inner sleeve 3^j is frictionally driven to drive the collar 13^j and thus the sleeve 12^j as hereinbefore described in connection with the corresponding parts 3, 13 and 12 in Figs. 1 to 11 and thus the return cam face 24^j is brought into engagement with the pin 18^j to worm the sleeve assembly away from the pinion. During this movement one end of the anti-bounce sleeve 3^j is left behind the adjacent end of the outer sleeve 12^j to absorb the momentum of the pinion when it is demeshed by the gear.

It will be noted in all these modifications that the chief features whereby the pinion may be turned first in one direction and then in the other during a continued movement of the lever, the anti-bounce device and the switch protection shoulder are common to all. It will be understood that the toothed clutches shown in most of the starters may be substituted by the cone clutch shown in Fig. 16 and vice versa, and that each of these clutches permits relative movement between the pinion and the manually operable outer sleeve to enable the latter to turn the pinion in both directions of rotation if necessary.

What we claim as our invention is:

1. In a mechanism for connecting a rotatable device with a gear, the combination with a pinion slidably connected with said device and adapted to be shifted into engagement with the gear, of manually operable means for shifting said pinion into engagement with the gear, said manual means including provisions which operate in case the pinion collides with the gear to produce rotation of said pinion in one direction of rotation while said pinion is pressed against the gear whereby said pinion may be brought into meshing relation with the gear, the said manual means also including provisions which operate in case a corner of a pinion tooth has jammed against a corner of a gear tooth to produce rotation of said pinion in a direction of rotation opposite to the first mentioned direction of rotation whereby said pinion will be moved to release the corner jam.

2. An engine starter comprising a rotatable

shaft having a starter pinion adapted to be driven thereby and moved endwise into mesh with a gear of an engine to be started; and pinion meshing means for axially moving the pinion and 5 for rotating it first in one direction of rotation in case the pinion collides with the gear and then in the opposite direction in case the pinion is prevented from turning in the first direction of rotation.

10. 3. An engine starter comprising a rotatable shaft having a starter pinion adapted to be driven thereby and moved endwise into mesh with a gear of an engine to be started; a sleeve slidable and rotatable relative to the shaft and having a 15 drive connection with the pinion; and means for axially moving the sleeve and for rotating the same first in one direction of rotation and then in the opposite direction to move the pinion into mesh with the gear.
20. 4. In a mechanism for connecting a rotatable device with a gear, the combination with a shaft driven by said device and a pinion splined thereto and shiftable into engagement with said gear, of a rotatable sleeve slidable relative to said 25 shaft; a manually operable member; camming provisions between the said sleeve and member to move the sleeve axially and to rotate it first in one direction of rotation and then in the other direction of rotation during one movement 30 of the manual member; and a clutch for transmitting the movements of the sleeve to the pinion, the clutch being adapted to slip in case rotation of the pinion is abnormally resisted.
35. 5. In a mechanism for connecting a rotatable device with a gear, the combination with a shaft driven by said device and a pinion splined thereto and shiftable into engagement with said gear, of pinion meshing means comprising a rotatable sleeve slidable relative to said shaft; a clutch 40 connecting said member and pinion; and a manually operable member, the sleeve having cam faces inclined in opposite directions for engagement with the manual member to move the sleeve axially and rotarily first in one direction of rotation and then in the other direction during one movement of the manual member, the first turning movement taking place in case the pinion collides with the gear and the second turning movement taking place in case the first turning 45 movement of the pinion be checked.
50. 6. In a mechanism for connecting a rotatable device with a gear, the combination with a pinion slidably connected with said device and adapted to be shifted into engagement with the gear, of manually operable means for shifting said pinion into engagement with the gear, said manual means including provisions for turning the pinion first in one direction of rotation and then in the opposite direction of rotation while the pinion is pressed against the gear, the first provisions operating to turn the pinion in case the pinion teeth abut those of the gear and the second provisions operating to turn the pinion in a reverse direction in case the first rotation therefore has not meshed the pinion.
55. 7. An engine starter comprising a shaft connected with a starter motor and having a starter pinion adapted to be driven thereby and moved endwise into mesh with a gear of an engine to be started; pinion meshing means comprising a rotatable sleeve slidable relative to said shaft and having a disengageable drive connection with the pinion; a manually operable member; camming means between the said members to move the rotatable sleeve axially and to rotate it first in one

direction of rotation and then in the other direction during one continuous movement of the manually operable member; a switch adapted to be closed by the manually operable member to energize the motor when the pinion is meshed with the gear; and means for limiting the relative movement of the member and pinion during the meshing of the latter to prevent the member from closing the switch before the pinion is meshed.

80. 8. An engine starter comprising a shaft connected with a starter motor and having a starter pinion adapted to be driven thereby and moved endwise into mesh with a gear of an engine to be started; pinion meshing means comprising a rotatable sleeve slidable relative to said shaft and having a disengageable drive connection with the pinion; a manually operable member, the sleeve having provisions for engagement by the manually operable member to axially move the sleeve and present the pinion to the gear and to rotate the sleeve first in one direction of rotation and then in the other direction; and means tending to rotate the sleeve when the shaft is rotating, the sleeve also having provisions for engagement by the manually operable member to return the sleeve to its initial position when the starter motor is energized.

85. 9. An engine starter comprising a shaft connected with a starter motor and having a starter pinion adapted to be driven thereby and moved endwise into mesh with a gear of an engine to be started; pinion meshing means comprising a rotatable sleeve slidable relative to said shaft and having a disengageable drive connection with the pinion; a manually operable member, the sleeve having provisions for engagement by the manually operable member whereby the sleeve is moved axially to present the pinion to the gear and is rotated first in one direction of rotation and then in the other direction; means tending to rotate the sleeve when the shaft is rotating, the sleeve also having provisions engageable by the manually operable member to return the sleeve to its initial position when the starter motor is energized; a switch adapted to be closed by the manually operable member to energize the motor when the pinion is meshed with the gear; and means for limiting the relative movement of the member and pinion during the meshing of the latter to prevent the member from closing the switch before the pinion is meshed and to position the member for engagement by the second mentioned provisions when the switch is closed.

90. 10. An engine starter comprising a shaft connected with a starter motor and having a starter pinion adapted to be driven thereby and moved endwise into mesh with a gear of an engine to be started; pinion meshing means comprising a rotatable sleeve slidable relative to said shaft and having a disengageable drive connection with the pinion; a manually operable member; releasable yielding means between the manually operable member and the rotatable member for axially moving the latter to present the pinion to the gear, the sleeve having provisions for engagement by the manually operable member whereby the sleeve is rotated in case the pinion teeth collide with the gear teeth, the yielding means being adapted to maintain the pinion in contact with the gear during the rotary movement of the pinion; a switch adapted to be closed by the manually operable member to energize the starter motor; means for limiting the movement of the manually operable member towards the switch if the pinion be not meshed with the gear; and

means for limiting the axial movement of the sleeve during the meshing of the pinion to ensure the release of the yielding means before the switch is closed.

- 5 11. An engine starter comprising a shaft connected with a starter motor and having a starter pinion adapted to be driven thereby and shiftable longitudinally thereof to mesh with a gear of an engine to be started; pinion meshing means comprising a rotatable sleeve slidable relative to said shaft for shifting the pinion axially and rotarily, the sleeve having a surface inclined to the axis thereof; and a manually operable member having provisions adapted to be engaged with the inclined surface to cause the sleeve and thus the pinion to be turned, the manually operable member having separate provisions for engaging the sleeve to cause an axial movement thereof to present the pinion to the gear.
- 10 12. An engine starter comprising a shaft connected with a starter motor and having a starter pinion adapted to be driven thereby and moved endwise into mesh with a gear of an engine to be started; a rotatable sleeve slidable relative to said shaft and provided with a lug; and manually operable means, including a pin and a spring finger for frictional engagement with opposite sides of the lug to move the sleeve axially to present the pinion to the gear.
- 15 13. An engine starter comprising a shaft connected with a starter motor and having a starter pinion adapted to be driven thereby and moved endwise into mesh with a gear of an engine to be started; a rotatable sleeve slidable relative to said shaft and provided with a lug inclined to the axis of the sleeve; a drive connection between the sleeve and the pinion; and manually operable means including provisions for frictional engagement with both sides of the lug to move the sleeve axially and present the pinion to the gear.

- 20 14. An engine starter comprising a shaft connected with a starter motor and having a starter pinion adapted to be driven thereby and moved endwise into mesh with a gear of an engine to be started; a rotatable sleeve slidable relative to said shaft and provided with a lug inclined to the axis of the sleeve; a drive connection between the sleeve and the pinion; and manually operable means including a pin for engaging one side of the lug and a spring finger for engaging the other side thereof to move the sleeve axially and rotarily and thus the pinion axially and, in case of gear tooth abutment, rotarily while the pinion is held by the pin and finger in contact with the gear.

- 25 15. An engine starter comprising a shaft connected with a starter motor and having a starter pinion adapted to be driven thereby and moved endwise into mesh with a gear of an engine to be started; a rotatable sleeve slidable relative to said shaft and provided with a lug inclined to the axis of the sleeve; a drive connection between the sleeve and the pinion; manually operable means including a pin for engaging one side of the lug and a spring finger for engaging the other side thereof to move the sleeve axially and rotarily to mesh the pinion with the gear; means tending to rotate the sleeve when the shaft is rotating; and means including a cam face on the sleeve engageable by the pin when the manually operable member is in its retracted position to prevent the rotation of the sleeve and position the finger to one side of the lug, the sleeve rotating means being adapted to cause the lug to be moved out of position for operative engagement by the

pin and finger should the manually operable member be actuated when the shaft is rotating.

16. An engine starter comprising a shaft connected with a starter motor and having a starter pinion adapted to be driven thereby and movable endwise into mesh with a gear of an engine to be started; pinion meshing means comprising a rotatable sleeve slidable relative to said shaft and having a disengageable driving connection with the pinion; a lug on the sleeve inclined to the axis thereof; a manually operable member adapted to engage one side of the lug to cause a rotary movement of the sleeve; means carried by the manual member for frictionally engaging the other side of the lug to move the sleeve axially, the sleeve having provisions for engagement by the manual member to rotate the sleeve in a direction of rotation opposite to that of its first mentioned rotary movement; means tending to rotate the sleeve when the shaft is rotating, the sleeve also having provisions for engagement by the manual member to return the sleeve to its initial position when the starter motor is energized; a switch adapted to be closed by the manually operable member to energize the motor when the pinion is meshed with the gear; and means for limiting the axial movement of the sleeve during the meshing of the pinion to ensure the friction means will be clear of the lug before the manually operable member closes the switch and to ensure the manually operable member being positioned for engagement by the second mentioned provisions when the switch is closed.

30 17. An engine starter comprising a motor having a rotatable shaft connected therewith; a starter pinion adapted to be driven by the shaft and moved endwise thereon into mesh with a gear of the engine to be started; pinion meshing means comprising a sleeve slidable and rotatable relative to the shaft and having a disengageable drive connection with the pinion; and manually operable means having operative engagement with the sleeve to mesh the pinion with the gear, the sleeve having provisions to free the said operative engagement between it and the manually operable means should the pinion contact with the gear while the latter is moving in either direction of rotation.

35 18. An engine starter comprising a motor having a rotatable shaft connected therewith; a starter pinion adapted to be driven by the shaft and moved endwise into mesh with a gear of the engine to be started; pinion meshing means comprising a sleeve slidable and rotatable relative to the shaft and having a disengageable drive connection with the pinion; manually operable means including a pin and slot connection with the sleeve for moving it to mesh the pinion with the gear, the sleeve having an opening communicating with the slot to permit the sleeve to rotate backwardly relative to the pin should the pinion contact with the gear while the latter is moving in a backward direction; and a switch closable by the manually operable means for energizing the starter motor when the pinion is meshed with the gear.

40 19. An engine starter comprising a motor having a rotatable shaft connected therewith; a starter pinion adapted to be driven by the shaft and moved endwise thereon into mesh with a gear of the engine to be started; a sleeve slidable and rotatable relative to the shaft and having a disengageable drive connection with the pinion; and manually operable means having operative engagement with the sleeve to mesh the pin-

ion with the gear, the sleeve having provisions to free the said operative engagement between it and the manually operable means should the pinion contact with the gear while the latter is moving in a backward direction.

20. An engine starter comprising a shaft connected with a starter motor and having a starter pinion adapted to be driven thereby and moved endwise into mesh with a gear of an engine to be started; a rotatable sleeve slidable relative to said shaft and having a disengageable drive connection with the pinion; a switch connected with the starter motor; manual means for actuating the sleeve to shift the pinion into mesh with the gear and for operating the switch to energize the motor when the pinion is meshed with the gear; means tending to rotate the sleeve when the shaft is rotating; and camming provisions between the sleeve and the manual means to return the sleeve to its initial position should the sleeve be given a backward rotary movement followed by a forward rotary movement.

21. An engine starter comprising a motor having a rotatable shaft connected therewith; a starter pinion adapted to be driven by the shaft and moved endwise thereon into mesh with a gear of the engine to be started; a sleeve slidable and rotatable relative to the shaft and having a disengageable drive connection with the pinion; manually operable means including a pin and slot connection with the sleeve for moving it to mesh the pinion with the gear; a switch operable by the manually operable means for energizing the starter motor when the pinion is meshed with the gear; and means tending to rotate the sleeve when the shaft is rotating, the sleeve being provided with a second slot having a face thereof inclined to the axis of the sleeve to engage the pin and return the sleeve to its initial position should the pinion and sleeve be given a backward rotary movement by the gear followed by a forward rotary movement of the sleeve by the shaft.

22. An engine starter comprising a motor having a rotatable shaft connected therewith; a starter pinion adapted to be driven by the shaft and moved endwise into mesh with a gear of the engine to be started; a sleeve slidable and rotatable relative to the shaft and having a disengageable drive connection with the pinion; manually operable means including a pin and slot connection with the sleeve for moving it to mesh the pinion with the gear; a switch operable by the manually operable means for energizing the starter motor when the pinion is meshed with the gear; and means tending to rotate the sleeve when the shaft is rotating, the sleeve being provided with a second slot having two faces thereof inclined to the axis of the sleeve in opposite directions, one of the faces being adapted to engage the pin to return the sleeve to its initial position should the pinion and sleeve be given a backward rotary movement by the gear and the other face being adapted to engage the pin to return the sleeve when the sleeve is given a forward turning movement by the shaft.

23. An engine starter comprising a rotatable shaft having a pinion threaded thereon for rotary movement therewith and for longitudinal movement thereof to mesh with a gear of the engine to be started; a slideable member; means for moving the member to mesh the pinion; and an anti-bounce device having relative axial movement with the member whereby one end of

the device will be positioned behind the adjacent end of the member during the return movement of the latter so that the device will be engaged by the pinion to absorb its momentum when it is de-meshed by the gear.

24. An engine starter comprising a rotatable shaft having a pinion threaded thereon for rotary movement therewith and for longitudinal movement thereof to mesh with a gear of the engine to be started, the threaded pinion being automatically de-meshed by the gear when the engine is started; a slideable outer sleeve; an anti-bounce device comprising an inner sleeve; means tending to rotate the inner sleeve with the shaft; a pin and connection between the inner and outer sleeves; manually operable means for moving the outer sleeve to mesh the pinion, the outer sleeve having provisions engageable by the manually operable means to return the outer sleeve when the shaft is rotated, the inner sleeve being moved axially with the outer sleeve when the latter is moved to mesh the pinion, the pin and slot connection being adapted to permit a relative axial movement of the inner and outer sleeves during the return movement of the sleeves to position the inner sleeve for engagement by the pinion to absorb its momentum when it is de-meshed by the gear.

25. An engine starter comprising a rotatable shaft having a pinion threaded thereon for rotary movement therewith and for longitudinal movement thereof to mesh with a gear of the engine to be started, the threaded pinion being automatically de-meshed by the gear when the engine is started; a slideable outer sleeve; a clutch connection between the outer sleeve and the pinion; an anti-bounce device comprising an inner sleeve having a drag connection with the shaft; a pin and slot connection between the outer and inner sleeves; manually operable means for moving the outer sleeve to mesh the pinion, the outer sleeve having provisions engageable by the manually operable means to return the outer sleeve when the shaft is rotated, the inner sleeve being moved axially with the outer sleeve when the latter is moved to mesh the pinion, the pin and slot connection being adapted to cause a relative axial movement of the inner and outer sleeves during the return movement of the sleeves to position the inner sleeve for engagement by the pinion to absorb its momentum when it is de-meshed by the gear; and means for limiting the return movement of the sleeves, the inner sleeve being positioned by the limiting means to limit the return movement of the pinion to prevent the engagement of the clutch while the parts are in their normal or initial positions.

26. An engine starter comprising a shaft connected with a starter motor and having a starter pinion threaded thereon for rotary movement therewith and for longitudinal movement thereof to mesh with a gear of an engine to be started; a clutch member disposed on the shaft and having a disengageable drive connection with the pinion; a sleeve disposed on the clutch member and having a rotary drive connection therewith; a spring tending to move the clutch member axially with the sleeve; a manually operable member; camming means between the manually operable member and the sleeve to move the latter axially and to rotate it; a switch closable by the manually operable member for energizing the motor; and means for limiting the movement of the manually operable member to prevent the

closing of the switch until the pinion is meshed with the gear.

27. An engine starter comprising a shaft connected with a starter motor and having a starter pinion threaded thereon for rotary movement therewith and for longitudinal movement thereof to mesh with a gear of an engine to be started; a clutch member disposed on the shaft and having a disengageable drive connection with the pinion; a sleeve disposed on the clutch member and having a rotary drive connection therewith; a spring tending to move the clutch member axially with the sleeve; a manually operable member, the sleeve having provisions for engagement by the manually operable member whereby the sleeve is moved axially to present the pinion to the gear and is rotated first in one direction of rotation and then in the other direction; a switch closable by the manually operable member for energizing the motor; means tending to rotate the sleeve with the shaft, the sleeve also having provisions engageable by the manually operable member to return the sleeve to its initial position when the motor is energized; means for limiting the movement of the manually operable member to prevent the closing of the switch until the pinion is meshed with the gear; and means for limiting the axial movement of the sleeve during the meshing of the pinion, whereby the manual operable member will be engaged with the first mentioned provisions to complete the rotary movement of the sleeve before it reaches its switch closing position in which the manually operable member is positioned for engagement by the second mentioned provisions for returning the sleeve.
28. An engine starter comprising a motor having a rotatable shaft connected therewith; a starter pinion adapted to be driven by and shiftable thereon to mesh with a gear of the engine to be started; a sleeve slidable and rotatable relative to the shaft and having a disengageable drive connection with the pinion, the drive connection being adapted to slip if the rotation of the pinion is abnormally resisted; and manually operable means including a pin and slot connection with the sleeve for moving the pinion axially and for rotating the sleeve in one direction, the sleeve having a second slot adapted to be engaged by the pin to rotate the sleeve in the opposite direction, the sleeve having a drag connection with the shaft and a third slot adapted to engage the pin to return the sleeve to its initial position when the shaft is rotated.
29. An engine starter comprising a rotatable shaft having a starter pinion adapted to be driven thereby and moved endwise into mesh with a gear of an engine to be started; a manually operable member; means including provisions actuated by the member for moving the pinion into mesh with the gear and for turning the pinion in one direction of rotation to effect meshing registration with the engine gear in case of gear tooth abutment, and provisions actuated by the member during a continuous movement thereof for turning the pinion in the opposite direction of rotation if the pinion is prevented from being turned by the first mentioned provisions; and means for permitting the member to continue its movement to actuate the second mentioned provisions.
30. Engine starting apparatus comprising in combination a motor, a shaft driven thereby, a pinion driven by the shaft and movable endwise into mesh with a gear of the engine to be started, an inner sleeve disposed on the shaft and adapted to abut the pinion; an outer sleeve disposed on the inner sleeve; a clutch member having a rotary drive connection with the outer sleeve and being axially movable relative thereto; a spring tending to maintain the clutch member in an extended position relative to the outer sleeve, the clutch member being adapted to engage the pinion to turn it under normal conditions and being adapted to slip if the turning of the pinion is abnormally resisted; a lug on the outer sleeve inclined to the axis thereof; a manually operable member having a pin and spring finger for frictional engagement with the lug, the outer sleeve having a cam face inclined to the axis thereof in a direction of inclination opposite to and steeper than the lug for engagement by the pin after the lug has been disengaged thereby; a switch closable by the manually operable member to energize the motor when the pinion is meshed with the gear; a pin and slot connection between the inner and outer sleeves adapted to limit the axial movement towards the gear of the outer sleeve relative to the inner sleeve; and a switch protection shoulder on the outer sleeve adapted to be engaged by the pin to limit the movement of the manual member relative to the said sleeve.
31. Engine starting apparatus comprising in combination a motor, a shaft driven thereby, a pinion driven by the shaft and movable endwise into mesh with a gear of the engine to be started, an inner sleeve disposed on the shaft and adapted to abut the pinion; an outer sleeve disposed on the inner sleeve; a clutch member having a rotary drive connection with the outer sleeve and being axially movable relative thereto; a spring tending to maintain the clutch member in an extended position relative to the outer sleeve, the clutch member being adapted to engage the pinion to turn it under normal conditions and being adapted to slip if the turning of the pinion is abnormally resisted; a lug on the outer sleeve inclined to the axis thereof; a manually operable member having a pin and spring finger for frictional engagement with the lug; an intermediate sleeve disposed on the inner sleeve behind the clutch member and having a pin and slot connection with the outer sleeve and being extended relative thereto by the said spring, the intermediate sleeve having a cam face inclined to the axis thereof, the outer sleeve having a cam face inclined to the axis thereof in a direction of inclination opposite to and steeper than the lug for engagement by the pin after the lug has been disengaged thereby; a switch closable by the manually operable member to energize the motor when the pinion is meshed with the gear; a pin and slot connection between the inner and outer sleeves adapted to limit the axial movement towards the gear of the outer sleeve relative to the inner sleeve; a drag connection between the shaft and the inner sleeve to tend to rotate the latter when the motor is energized; a return cam face on the outer sleeve adapted to engage the pin to return the outer sleeve to its initial position when the shaft is rotated by the motor; a face on the outer sleeve having a steeper angle of inclination than the first mentioned cam face and normally adapted to overlie the latter and to be engaged by the pin on the manual member to expose the said cam face for engagement by the said pin, the spring being adapted to return the sleeves and clutch member to their normal extended positions when the pinion teeth clear the gear teeth so that

the steeply inclined face on the outer sleeve will be moved past the pin to facilitate the engagement of the return cam face therewith when the starter motor is energized.

5 32. An engine starter comprising a rotatable shaft having a starter pinion adapted to be driven thereby and moved endwise into mesh with a gear of an engine to be started; a cone clutch member disposed on the shaft and adapted to 10 engage the pinion; and means for axially moving the clutch member and for rotating the same first in one direction of rotation and then in the opposite direction to move the pinion into mesh with the gear.

15 33. An engine starter comprising a rotatable shaft having a starter pinion adapted to be driven thereby and moved endwise into mesh with a gear of an engine to be started, the pinion being provided with a conical surface; a clutch member 20 disposed on the shaft and having a conical surface for frictional engagement with the first mentioned surface; an outer sleeve connected with the clutch member and provided with a slot inclined to the axis of the sleeve; a manually operable member having a pin received in the slot; 25 an intermediate sleeve having a lug adapted to be located relative to the slot for engagement by the pin; and a spring tending to retain the clutch member and intermediate sleeve in their extended 30 positions.

34. An engine starter comprising a rotatable shaft having a starter pinion adapted to be driven thereby and moved endwise into mesh with a gear of an engine to be started; an outer sleeve 35 disposed on the shaft and provided with a slot inclined to the axis thereof; a rotary drive connection between the sleeve and pinion adapted to slip if the turning movement of the pinion be abnormally resisted; a manually operable 40 member having a pin received in the slot; an intermediate sleeve having a lug adapted to be engaged by the pin; a pin and inclined slot connection between the outer and intermediate sleeves, the inclination of the last mentioned slot 45 being such that the lug will follow the inclination of the first mentioned slot; and a spring tending to maintain the lug engaged with the manually operable pin.

50 35. A starter constructed as set forth in claim 34 in which the lug is inclined to the axis of the outer sleeve in a direction opposite to that of the first mentioned slot and in which the latter communicates with an opening in the outer sleeve to provide clearance between the adjacent 55 sides of the opening and lug for the manual pin to ride over the side of the lug and thus reverse the direction of rotation of the pinion.

60 36. Engine starting apparatus, comprising in combination, a motor, a shaft driven thereby, a pinion driven by the shaft and movable endwise into mesh with a gear connected with the engine to be started, manually operable means for moving the pinion into mesh with the engine gear and operable to rotate the pinion normally in one direction in case of gear tooth 65 abutment, and means whereby the pinion may be rotated in a different direction while being pressed against the engine gear, in case rotation of the pinion in the first direction is abnormally resisted.

70 37. Engine starting apparatus comprising, in combination, a motor, means for connecting the motor with a gear of an engine to be started,

said means comprising a pinion driven by the motor and movable endwise into mesh with the engine gear and provision whereby the pinion will be automatically disconnected from the engine gear when the engine starts, and manually operable means for moving the pinion into mesh with the engine gear and operable to rotate the pinion normally in a certain direction in case of gear tooth abutment, and having provisions operable to rotate the pinion in a different direction, 80 while being pressed against the engine gear, in case rotation of the pinion in the first direction is abnormally resisted, said manually operable means including an actuator, and provisions for automatically retracting the pinion moving means from the pinion before the engine starts regardless of whether the actuator has been released.

85 38. An engine starter comprising a rotatable shaft having a pinion threaded thereon for rotary movement therewith and for longitudinal movement thereof to mesh with a gear of the engine to be started, the threaded pinion being automatically de-meshed by the gear when the engine is started; a slideable outer sleeve; an anti-bounce device comprising an inner sleeve; means tending to rotate the inner sleeve with the shaft; a pin and inclined slot connection between the inner and outer sleeves; manually operable means for moving the outer sleeve to mesh the pinion, 100 the outer sleeve having provisions engageable by the manually operable means to return the outer sleeve when the shaft is rotated, the inner sleeve being moved axially with the outer sleeve when the latter is moved to mesh the pinion, the pin 110 and inclined slot connection being adapted to cause a relative axial movement of the inner and outer sleeves during the return movement of the sleeves to position the inner sleeve for engagement by the pinion to absorb its momentum when 115 it is de-meshed by the gear.

105 39. An engine starter comprising a rotatable shaft having a pinion threaded thereon for rotary movement therewith and for longitudinal movement thereof to mesh with a gear of the 120 engine to be started, the threaded pinion being automatically de-meshed by the gear when the engine is started; a slideable outer sleeve; a clutch connection between the outer sleeve and the pinion; an anti-bounce device comprising an inner 125 sleeve having a drag connection with the shaft; a pin and inclined slot connection between the outer and inner sleeves; manually operable means for moving the outer sleeve to mesh the pinion, the outer sleeve having provisions engageable by 130 the manually operable means to return the outer sleeve when the shaft is rotated, the inner sleeve being moved axially with the outer sleeve when the latter is moved to mesh the pinion, the pin 135 and inclined slot connection being adapted to cause a relative axial movement of the inner and outer sleeves during the return movement of the sleeves to position the inner sleeve for engagement by the pinion to absorb its momentum when it is de-meshed by the gear; and 140 means for limiting the return movement of the sleeves, the inner sleeve being positioned by the limiting means to limit the return movement of the pinion to prevent the engagement of the clutch while the parts are in their normal or 145 initial positions.

MAUNSELL B. JACKSON.
KENNETH M. CLIPSHAM.
